HOWARD M. KIRBY, OF WILMINGTON, DELAWARE.

DRAIN-VALVE.

934,188.

Specification of Letters Patent. Patented Sept. 14, 1909.

Application filed September 6, 1907. Serial No. 391,619.

To all whom it may concern:

Be it known that I, HOWARD M. KIRBY, a citizen of the United States, and a resident of Wilmington, in the county of Newcastle and State of Delaware, have invented a new and Improved Drain-Valve, of which the following is a full, clear, and exact description.

This invention relates to drain valves, and 10 is especially adapted to be used in connection with bathtubs, wash bowls and the like.

The object of the invention is to produce a valve of simple construction, having means for normally holding the valve wide open, 15 the valve having such a construction as will enable the valve to be locked by a simple movement, in its closed position.

The invention consists in the construction and combination of parts to be more fully 20 described hereinafter and particularly set forth in the claims.

Reference is to be had to the accompanying drawings forming a part of this specification, in which similar characters of reference indicate corresponding parts in all the 25 figures.

Figure 1 is a vertical section through the edge and bottom of a tub to which the invention has been applied; the lower portion of 30 the valve is shown in cross section and the other parts are shown in elevation; Fig. 2 is a vertical section through the lower portion of the valve, upon an enlarged scale, and showing the parts in the relation they 35 assume when the valve is closed; this view is a section on the line 2—2 of Fig. 3; Fig. 3 is a horizontal section on the line 3—3 of Fig. 2; and Fig. 4 is a vertical section through the handle of the valve; that is, at 40 the upper edge of the tub, from which point the valve is operated.

Referring more particularly to the parts, 1 represents the side of the tub, having a roll or flange 2 formed at its upper edge, and a bottom 3, the said flange being a continuance 45 of the side wall 1 as shown. At a suitable point near the bottom of the tub, I provide a valve body 4 which is connected at one side by a horizontal drain connection 5, with 50 the main drain or outlet 6 from the bottom of the tub. The upper side of this valve body is connected with an overflow pipe 7 which extends vertically upward, and is connected with the overflow drain or outlet 8 55 mounted in the side of the tub, the connec-

tion at this point being effected by means of a suitable elbow 9.

The lower side of the valve body 4 is connected with the drain pipe 10. The interior of the valve body 4 at its point of connection 60 with the drain connection 5, is formed into a valve seat 11, as illustrated most clearly in Fig. 2. In the interior of the valve and in the upper portion thereof, an ear 12 is provided, to which a valve lever 13 is pivotally 65 attached. The lower end of this valve lever 13 is rigidly connected to a valve disk 14 which is of rounded or cup form, the convex side of the cup being disposed toward the drain connection 5. On the inner face of this 70 valve disk 14 a washer or packing cup 15 is attached. As illustrated, the diameter of the disk 14 is considerably less than that of the seat 11, so that the edges of the packing cup 15 project beyond the disk 14 and come 75 against the seat 11 as shown. To the end of the lever just behind the central point of the disk 14, a strut or link 16 is pivotally 80 attached, and the interior of the valve body opposite to the central point of the disk 14, is provided with a shoulder or stop 17 which projects inwardly as shown. Just above this stop 17 a small recess or groove 18 is formed in the wall of the valve body, which is slightly increased in thickness at this point 85 as shown. The free end of the link 16 is rounded as shown, so that when the valve is closed, the link lies in a horizontal position, its free end being held in the groove, recess or notch 18. In this connection, it 90 will be understood that the resiliency of the packing cup 15 insures that the link will hold itself in position as shown.

Near the middle point of the link 16, a saddle 19 is pivotally attached, and this saddle is provided with a threaded bolt 20. To this threaded bolt 20 a valve stem 21 is attached, the connection including an enlargement or head 22 formed on the body of the bolt near the saddle. This arrangement is 95 adopted for practical reasons as it enables the stem to be removed when the parts are to be shipped. The valve stem passes up through the upper portion of the elbow 9, and extends through a suitable opening 23 100 formed in the edge or flange 2 of the tub, as shown. To the extremity of the stem a knob 24 is rigidly attached, and this knob is formed on its lower side with downwardly 105 projecting teeth 25, which may be four in 110

number as shown. These teeth are adapted to be received in notches 26 formed in a knob seat 27, which knob seat is attached to the upper side of the flange of the tub, being 5 formed with a suitable nipple 28 which passes downwardly through the opening 23 and receives a clamping nut 29, as shown most clearly in Fig. 4. Between the adjacent faces of the knob and knob seat, a spring 10 chamber 30 is formed, in which there is received a helical spring 31. This spring is a compression spring, and tends to hold the stem in a much elevated position, as indicated in Fig. 1. This position of the stem 15 holds the valve in a wide open position, the opening movement of the valve being arrested by the stop or projection 17 which is struck by the lower edge of the packing cup 15. The teeth 25 and the notches 26 have 20 inclined meeting faces as shown.

In order to close the valve, the knob 24 is pushed downwardly so that the link 16 moves down into the horizontal position shown in Fig. 2. In doing so, the end of the 25 link 16 snaps into the detent notch 18 intended to receive it, and this holds the valve in its closed position. When the valve is to be opened, a slight rotation of the knob operates to draw the stem 21 upwardly, by reason of the fact that the inclined edges of the 30 teeth 25 slide on the inclined edges of the notches 26. In this way the opening movement of the valve is initiated, and enables the end of the link 16 to free itself. As soon 35 as this occurs, the spring 31 extends itself and opens the valve to the wide open position.

Special attention is called to the fact that when the valve is closed, the overflow pipe is 40 unobstructed. When the valve is closed, it will be observed that the link 16 operates as a strut, jammed as it is between the back of the disk and the valve body.

The fact that the link 16 is pivotally attached to the valve disk, enables the stem to 45 operate it by a simple longitudinal movement in the guide openings for the stem.

Having thus described my invention, I claim as new and desire to secure by Letters 50 Patent:

1. In combination, a valve body having a valve seat, a movable valve disk adapted to

close against said seat, a stem, a member connecting said stem with said valve disk, and projecting across the interior of said 55 valve body, and a spring in connection with said stem tending to raise the same and hold said valve disk open, said body having a recess adapted to receive the end of said member when said disk is moved to its closed position, said member being adapted to snap into said recess whereby said body affords means for holding said member against the force of said spring.

2. In combination, a valve body having a 65 valve seat, a valve disk pivotally mounted within said body and closing upon said seat, a link pivotally attached at the back of said disk and extending across the interior of said body, a stem pivotally attached to said link, and a spring in connection with said stem tending to raise the same and open 70 said disk, said valve body having a recess adapted to engage the end of said link when in its closed position, said recess affording 75 means for retaining said link in its closed position against the opening force exerted by said spring.

3. A valve body having a seat, a valve disk 80 pivotally mounted within said body and adapted to move upon said seat, a link pivotally attached to said disk and extending across the interior of said body, a stem pivotally attached to said link, a spring in connection with said stem tending to raise the same and open 85 said disk, said valve body having detent means formed on the wall and engaging and retaining said link against the force of said spring when said disk is in its closed position, a knob carried by said stem, and means for giving said stem an upward 90 movement by the rotation of said knob to disengage said link from said detent means, said spring affording means for opening said disk when said link is released from said detent means.

In testimony whereof I have signed my name to this specification in the presence of two subscribing witnesses.

HOWARD M. KIRBY.
